UNITED STATES PATENT OFFICE.

MOTT BILLINGS BROOKS, OF NORTH HAMMOND, NEW YORK.

DOUBLE-ACTING SUBMERGED FORCE-PUMP.

SPECIFICATION forming part of Letters Patent No. 317,714, dated May 12, 1885.

Application filed October 20, 1884. (No model.)

To all whom it may concern:

Be it known that I, MOTT B. BROOKS, a citizen of the United States, residing at North Hammond, in the county of St. Lawrence and 5 State of New York, have invented certain new and useful Improvements in Double-Acting Submerged Force-Pumps; and I do hereby declare that the following is a full, clear, and exact description of the same, reference being had 10 to the annexed drawings, making a part of this specification, and to the letters and figures of reference marked thereon.

Figure 1 of the drawings is a sectional elevation of my improved pump. Fig. 2 is a detail 15 plan view of the upper valve-seat; Fig. 3, a similar view of the valve; Fig. 4, a plan view of the lower end of the cylinder; Fig. 5, a similar view of the lower valve, and Fig. 6 a partial 20 sectional detail taken at right angles to Fig. 1. The present invention has relation to certain new and useful improvements in double-acting submerged force-pumps; and it consists in the 25 details of construction substantially as shown in the drawings and hereinafter described and claimed.

In the accompanying drawings, A represents the pump-cylinder, having interior screw-threads upon its lower end for attaching thereto a perforated valve-seat, B, and a central hole 30 to receive a guide-pin, a, for the valve C.

Within the cylinder A works a hollow piston-rod, D, which extends up through a head, E, and cap F, the latter having connected thereto an operating rod or lever, b. The head E is provided with an exterior screw-threaded flange, 35 c, for engaging with interior screw-threads upon the upper end of the pump-cylinder A. The upper portion of the head E is cast or otherwise provided with an interior screw-threaded flange or rim, d, with which engages the screw-threaded flange e of the cap F. The head E is also cast with a valve-seat, f, having inlets g, which communicate with the chamber G, formed by the flanges e between the cap and 40 head, a valve, H, controlling the inlets g. The lower end of the hollow piston-rod D is screw-threaded, and has connected thereto a tubular piston-section, I, which passes loosely through the plunger-head K, consisting of the two sections h i and packing k, of leather or other suitable material. The tubular section I, near its up-

per end, has perforations l, and near its lower end perforations m, for the discharge of the water into the piston-rod D. The ends of the tubular section I are provided with stationary 55 valves L M, which act in conjunction with the plunger-head K.

In Fig. 1 of the drawings the cylinder A is shown as being pressed down, the inlets g being closed by valve H, as are also the perforations m in the tubular section I, the valve L closing tightly against the under side of the plunger-head K, which forms a seat therefor. The water is forced from the upper part of the cylinder down and through the upper perforations, l, and up the hollow piston-rod D. The pressure of water in the well causes the valve 60 C to rise, which opens the perforations in the valve-seat B, and thus allows the water to enter the cylinder A and fill that portion thereof below the plunger-head K. The cylinder A having completed its downward stroke, the valve 65 C closes, and on its upward stroke carries with it the plunger-head K, and, as the head strikes the under side of the valve M, closes the perforations l and opens the perforations m, the water being forced from the lower part of the cylinder through the perforations m and up the piston-rod D. The pressure of the water in the well causes the valve H to rise, and allows the 70 water to pass into the chamber G through inlets g, and thence down through openings n in the valve-seat f, which fills that portion of the cylinder A above the plunger-head K. The pins p, which pass through the valve H, are to 75 prevent it from turning.

I am aware that submerged-pump cylinders have been provided with a removable cap, forming an annular chamber between the cap and the end of the cylinder, which latter forms 80 a seat for a valve confined between the end of the cylinder and the cap to regulate ports formed in the end of the cylinder, and do not claim such, for where the peculiarity consists in the construction of the cylinder, as in the 85 above case, the production of the same is at a much higher cost, comparatively, than my device, where the peculiarity of construction is solely in the head, which latter can be produced cheaply and used in connection with 90 any cylinder or tube.

Having now fully described my invention,

what I claim as new, and desire to secure by Letters Patent, is—

In a double-acting submerged pump, a pump-cylinder provided at its lower end with a perforated valve-seat and valve, and at its upper end with a removable head having an annular chamber formed therein, with inlets leading from the exterior and interior of the cylinder to said chamber, and a valve located within

10 said chamber and controlling the inlet-ports,

in combination with a hollow piston-rod and plunger-head, as and for the purposes set forth.

In testimony that I claim the above I have hereunto subscribed my name in the presence of two witnesses.

MOTT BILLINGS BROOKS.
